UNITED STATES PATENT OFFICE.

LOUIS ALEXANDRE CADORET, OF PAWTUCKET, RHODE ISLAND.

BOBBIN RETAINER.

Application filed April 16, 1923. Serial No. 632,444.

To all whom it may concern:

Be it known that I, LOUIS A. CADORET, a citizen of the United States, residing at Pawtucket, in the county of Providence and State of Rhode Island, have invented certain new and useful Improvements in Bobbin Retainers; and I do declare the following to be a full, clear, and exact description of the invention, such as will enable others skilled in the art to which it appertains to make and use the same.

This invention relates to an improved bobbin retainer of the type which is intended to be permanently secured to the shuttle and to grip the bobbin to retain the latter in operative position so as to permit the usual pivoted spindle to be entirely dispensed with.

The principal object of the invention is to generally improve upon retainers of this type and to provide one of extreme simplicity and durability which is composed of a single length of resilient wire so designed as to provide unique attaching means and gripping jaws.

It is also an object of the invention to provide a retainer of this type which is so designed as to permit it to be attached to the shuttle without requiring extensive alteration thereof, yet insuring against accidental displacement or loose movement of the retainer.

In the drawings:

Figure 1 is a top plan view of one end of a conventional type of shuttle showing the improved bobbin retainer connected therewith.

Figure 2 is a bottom plan view of Fig. 1.

Figure 3 is a side elevation with portions broken away and shown in section to disclose the construction of parts more clearly.

Figure 4 is a transverse vertical section taken on the line 4—4 of Fig. 3.

Figure 5 is a detail perspective view of the improved retainer.

In the drawings, the reference character S designates a conventional type of shuttle and B designates an ordinary bobbin which is used in connection therewith.

As before intimated, it is my aim to eliminate the usual pivoted spindle and to provide a unique type of retainer for directly engaging the bobbin and holding it in operative position. Probably the retainer could be constructed otherwise, but by preference it is formed from a single length of wire

which is bent between its ends as indicated at 1 to provide a pair of spaced parallel upper attaching arms 2. These arms are bent at right angles as at 3 to provide what may be conveniently termed abutments. Beyond the abutments, the arms are bent into parallelism as at 4 and are directed laterally inward at 5, then down at right angles and bowed outwardly so as to form substantially arcuate gripping jaws 6 adapted for reception in the usual groove in the head of the bobbin B. The wire is extended from the lower ends of the jaws as at 7 to form a pair of lower attaching arms and the free extremities of these are bent laterally as at 8 to serve a purpose to be hereinafter described. With the form of retainer described, it is obvious that it is only necessary to form comparatively shallow recesses R in the left-hand end of the shuttle.

In applying the retainer to the shuttle, the pairs of upper and lower attaching arms are permitted to straddle the web W of the shuttle. This web is formed near its free end with a vertical bore and a bolt 9 is passed through the bore, this bolt being employed for the purpose of retaining the plate 10 in place against the undergrooved side of the web. As clearly shown in Fig. 4, this plate extends cross-wise of the free ends of the attaching arms 7 and when the nut on the upper end of the bolt is tightened, the plate is bound tightly against the arms and the latter are in turn bound against the web so as to securely maintain the bobbin retainer in place. It is also to be noted, as seen in Fig. 3, that the laterally directed ends 8 of the lower attaching arms abut the adjacent edge of the plate 10 and prevent twisting or rotation of the retainer.

In use, it is obvious that the portion of the head of the bobbin beyond the usual groove is received between the so-called abutments 3 and the laterally bent portions 5, the curved jaws 6 being received in the groove and serving to tightly hold the bobbin in place.

I claim:

1. A bobbin retainer of the type specified, comprising attaching arms provided adjacent one end with U-shaped portions for accommodating a portion of the head of the bobbin, the outer ends of said arms being directed vertically for reception in the usual groove in said head.

2. A bobbin retainer of the character

specified, formed from a single length of wire bent between its ends to provide attaching arms, portions of said arms adjacent the outer ends thereof being bent to provide substantially U-shaped portions for accommodating a portion of the head of the bobbin, the wire beyond said U-shaped portions being directed at right angles to provide portions for reception in the usual groove of said bobbin head.

3. A bobbin retainer formed from a single length of wire bent between its ends to form a pair of attaching arms, said arms being bent adjacent one end to provide substantially U-shaped portions and being then bent downwardly and bowed outwardly to provide substantially arcuate gripping jaws, the ends of the wire being bent at right angles from said jaws to extend in spaced parallelism with the first named attaching

arms to provide a pair of lower attaching arms, the extremities of said lower arms being bent laterally.

4. A bobbin retainer formed from a single length of wire bent between its ends to provide spaced attaching arms, said arms being bent adjacent their outer ends to provide opposed U-shaped portions for accommodating a portion of the head of the bobbin, the wire beyond said U-shaped portions being directed downwardly at right angles and bowed outwardly to provide arcuate portions for reception in the usual groove in the head of the bobbin, the extremities of the wire being bent into parallelism with said first named arms to provide lower attaching arms.

In testimony whereof I have hereunto affixed my signature.

LOUIS ALEXANDRE CADORET.
